UNITED STATES PATENT OFFICE.

EPHRAIM H. FENTON, OF KANSAS CITY, MISSOURI.

BOX-FASTENER.

SPECIFICATION forming part of Letters Patent No. 555,688, dated March 3, 1896.

Application filed August 10, 1895. Serial No. 558,918. (No model.)

To all whom it may concern:

Be it known that I, EPHRAIM H. FENTON, a citizen of the United States, residing at Kansas City, in the county of Jackson and State 5 of Missouri, have invented certain new and useful Improvements in Boltwork for Adjustable Covers to Egg-Boxes; and I do hereby declare that the following is a full, clear, and exact description of the invention, such 10 as will enable others to make and use the same, reference being had to the accompanying drawings, forming a part of this specification.

My invention has for its object to obtain an increased power to throw the bolt and simultaneously lock the same in position; and it 15 consists in the novel construction and combination of parts, such as will be first fully described, and specifically pointed out in the claims.

20 In the drawings, Figure 1 is a broken plan view of an egg-case and its adjustable cover, showing the improved boltwork applied thereto. Fig. 2 is a broken vertical sectional view of the egg-case and cover, taken upon the line x x of Fig. 1, showing the rock-shaft hanger and operating-lever in section. Fig. 3 is a plan view showing an alternate construction of boltwork. Fig. 4 is a longitudinal sectional view of the hanger and cam as seen in 25 Fig. 3.

30 Similar letters of reference indicate corresponding parts in all the figures.

Referring to the drawings, A represents an egg-case for the transportation of eggs, which 35 is of the usual construction. The adjustable cover B is fitted to the inner sides of the case A, so as to be readily moved in position without binding.

40 To the upper side of the cover B is attached a cleat b, which extends along one edge of the cover adjacent to the inner side of the box. Parallel with cleat b and to the top of said cover, near the opposite side of said box, is attached a cleat b'. At a point equidistant from 45 the cleats b b' and to the upper side of the cover B is secured by screws c c a shaft-hanger C, in which is a transverse rock-shaft d. To one end of shaft d, on one side of hanger C, is attached eccentrically a circular plate d', and to the other end of said shaft is attached 50 eccentrically a circular plate d'', the eccentric portion of the plate d' extending in one direc-

tion and the eccentric portion of the plate d'' in the opposite direction.

At one end of the base of the hanger C, 55 which is secured flatwise to the upper portion of the cover B, and extending at right angles therefrom near the screw c, is a spring bearing or guide c', at the outer end of which is a nib c''. At the other end of the base of hanger C and on the other side from that having the spring-bearing c' are a bearing c³ and nib c⁴, which are precisely the same as the bearing c' and nib c''. Upon the bearing c' within the nib c'' is placed one end of a flat spring E, the 60 other end of which spring extends parallel with the hanger C and in the direction of the other end of the portion of the base of hanger C and a short distance beyond said end portion, and is secured by the nail e to the upper 65 side of said top B of the box. On the other side of the hanger C is a flat spring E', one end of which is supported upon the bearing c³ and the other end extends parallel with 70 said hanger and the corresponding distance 75 beyond the end of said hanger and is secured to the upper side of the cover B in the same manner as described of the spring E.

F represents one of the bolt-rods, which consists of a single piece of stout wire, one end of 80 which is chisel-pointed, as at f^x, and extends through a transverse perforation b^x made in the cleat b near the upper surface of the top B of the box. The other end of the wire is extended in the direction of the under-side 85 portion of eccentric d' and nearly to said eccentric-plate; thence bent at f at right angles in an upward direction and over the outer edge of said plate, terminating near the angle f and forming a loop f''. In the cleat b' is an 90 opening b⁰, through which is inserted one end of a bolt-rod F', which end is provided with a sharp chisel edge f⁰. The other end of said bolt is extended in the direction of the under-side portion of the eccentric-plate d'' and at a 95 point near thereto is bent over the circular edge of said plate in the same manner as described of the bolt-rod F, forming a loop f'', which bolts F F' yield slightly when the bolt-rod meets with resistance.

100 G is the operating-lever, which consists of the handle g, which is bent or curved upwardly, so as to be readily seized by the hand, and the forked portions g' g², which are con-

nnected rigidly with the respective ends of the rock-shaft d on opposite sides of the hanger C and with the handle g a considerable distance from said bracket, so as to avoid contact with the hanger in the reversal of position. The forked end g' is also extended from rock-shaft d a considerable distance in the same direction, corresponding to the distance between said shaft and the spring-plate E' at 10 a depressed point, the upper and lower edges of which end g' are inclined at an angle from said handle g upwardly and outwardly in one direction, and in the direction of the top B of the case in the other, the lower end of which 15 extended portion of said forked end is curved so as to form a cam g^3 . The other forked end, g^2 , is precisely the same as the end g' and is provided with a cam g^4 , which is the same as cam g^3 , it being observed that the inclined 20 edge of each forked end at its junction with the cam is pointed and bears directly on the respective spring-plates.

In Fig. 3 I have shown a modification of the invention, and in place of the springs $E E'$, I 25 employ but one spring H , which is fitted in the slot h in the base of the hanger H' , and supported at each end by an inclined seat at each end of the hanger. On the rock-shaft I is a cam i , which comes into contact with 30 and depresses the spring H , and by it the cam is retarded in movement. The forked end k of the handle K is also forked at $k^2 k^3$, the portion k^2 being directly attached to the rock-shaft and the portion k^3 having a loop k^4 , 35 which extends to a point in line with the rock-shaft. The other forked end of the handle K is also forked in the same manner as the end k , the loop k^5 being extended, however, past the line of the rock-shaft a short distance, and performs the same duty as the eccentric-plates in Figs. 1 and 2. The bolt-rods in this construction I prefer to make 40 from a single wire of suitable length, which is bent at a point equidistant from each end to form a loop, which also embraces the loop k^4 on the forked end of the handle K , and the two ends placed in a parallel position and twisted together to a point a short distance from the cleat, at which point the ends are 45 divided and bent outwardly at an angle to the main portion of the twisted wire, and again in the direction of the cleat and through suitable perforations, as described, of the bolt F .

In the operation of my invention the cover 50 B is first adjusted to position at the desired height from the bottom of the box and the lever-handle operated to throw the bolt-rods within the surface of the inner side of the box, and the cover is secured in that position.

As seen in Figs. 1 and 2, the handle g is bearing firmly upon the upper side of the cover B and locked automatically in that position by the pointed end of the cams $g^2 g^3$. In order to release the boltwork the handle g of the lever is seized by the hand and reversed in 60 position, as seen in dotted lines, which operates the rock-shaft and partially rotates the eccentrics in the loops $f' f^2$, and the bolt-rods $F F'$ are withdrawn from the sides of the box within the openings in the cleats $b b'$. In operating the lever G , I am enabled to force the bolt-rods within the hard variety of wood with but little resistance. This resistance, however, being thrown on the loops of the bolts, which yield, prevents the breaking of 65 the bolt-rods under the strain. In the reversal of the lever G , in Fig. 1, the cams $g^3 g^4$, which are controlled by the springs $E E'$, operate to equalize the outward thrust when power is applied to the rock-shaft. In Fig. 70 3 this is accomplished by the spring H and the bearing outward.

Having fully described my invention, what I now claim as new, and desire to secure by Letters Patent, is—

1. In boltwork for the adjustable cover to egg-boxes the combination with said cover of a shaft-hanger a rock-shaft circular plates connected eccentrically with said rock-shaft and having the eccentric portions extending 90 in opposite directions, an operating-lever having forked ends connected with said rock-shaft, oppositely-movable bolt-rods in suitable guides on said cover having an engaging point at their outer end and a loop adapted to yield on the inner end of said rods extending over said eccentric-plates as and for the purpose described.

2. In boltwork for the adjustable cover to egg-boxes the combination with said cover of a shaft-hanger a rock-shaft circular plates connected eccentrically with said shaft and having the eccentric portions extending in opposite directions oppositely-movable bolt-rods in suitable guides on said cover having 100 loops adapted to yield upon their inner ends extending over said eccentric-plates, a spring on said hanger supported at each end and an operating-lever having a forked portion connected with said rock-shaft and an extension 105 of said forked portion having a cam bearing upon the said spring whereby the upward movement of the free end of the lever is retarded, as described.

EPHRAIM H. FENTON.
